RADIATOR OF AEROPLANE ENGINES

Louis Maurice Lachasse, Paris, France, assignor
to Societe Anonyme des Appareils G. A. L.,
Neuilly-sur-Seine, France, a corporation of
France

Application December 9, 1936, Serial No. 114,915
In France December 24, 1935

4 Claims. (Cl. 257—125)

The present invention has for its object to produce a radiator for the cooling of aeroplane engines which offers a minimum resistance against advance through the air.

5 A further object is to provide a radiator having a relatively small front surface and a great depth which radiator is easy to manufacture and shows a maximum safety as regards watertightness.

10 Still further objects are to facilitate the possible repairs in radiators of great depth, and to avoid the construction of headers of too great a capacity in order to prevent risks of bursting.

15 The radiators enabling the aforesaid objects to be obtained have the features which will be apparent from the following description and the accompanying claims.

20 Radiators according to the invention are illustrated by way of example in the accompanying drawings in which:

Fig. 1 is a front view of a radiator built up of blade elements.

Fig. 2 is a plan view of said radiator.

Fig. 3 is a side elevation of said radiator.

25 Fig. 4 is an enlarged section along 4—4 of Fig. 1.

Fig. 5 is an enlarged section along the line 5—5 of Fig. 2.

Fig. 6 is a section along the line 6—6 of Fig. 5.

30 Fig. 7 is a partial perspective view of a radiator element of Figs. 1 to 3.

Fig. 8 is a front view of another radiator according to the invention.

35 The cooling radiator illustrated in Figs. 1 to 7 has radiating elements consisting of parallel blades which provide on the one hand between them spaces for the free passage of the cooling fluid and, on the other hand, spaces for the circulation of the fluid to be cooled.

40 The radiator essentially comprises a plurality of elements 1¹, 1², 1³ . . . juxtaposed to each other in the direction of the circulation of the current of air, moving in the direction of the arrow F¹. Each radiator element 1¹, 1², 1³ . . . has a depth p

45 which permits ready access to all the members forming said element, for example for cleaning and repairing said element.

The various radiator elements 1¹, 1², 1³ . . . are assembled consecutively to each other, to form 50 a radiator with a relatively great depth P which gives said radiator a maximum efficacy and efficiency, and a relatively small front surface.

Each radiator element 1¹, 1², 1³ . . . has two lateral headers 1—2 for the inlet of the liquid to 55 be cooled and a central header 3 for the outlet

of the cooled liquid; the central header 3, however, can be omitted and, in this case, one of the side headers 1 serves for the inlet of the liquid to be cooled, whereas the other side header 2 is used as the outlet for the cooled liquid.

5 The radiating network interposed between the headers 1, 2 and 3 comprises hollow parallel blades 4 arranged horizontally and providing between the free spaces 5 for the passage of the current of cooling air F.

10 Each of the headers 1, 2, 3 is connected at its upper part to a tube 8 which, on the one hand, itself forms a header and on the other hand serves for the assembly of the various radiator elements 1¹, 1², 1³ . . .

15 The tubes 8 of two adjacent radiator elements are connected to each other (Fig. 4) by male and female nipples 10, 11 fitting into each other and clamping a sealing joint 12 between them. At each end of the radiator the tubes 8 of the first 20 and of the last elements are closed by a plug 13.

20 The inlet and the outlet of the liquid to be cooled are effected by means of nipples 16, 17, 18 provided on the tubes 8 of one of the elements and arranged perpendicularly to said tubes.

25 Said inlet nipples 16 and 17 and outlet nipple 18 need not be disposed upwardly, as shown in Figs. 1 to 3 of the drawings, but can be provided on the tubes 8 in any favourable position according to the particular installation.

30 In this manner, a very simple and tight connection between individual elements is obtained without rubber hoses and collars, and a considerable decrease in weight, bulk and cost of manufacture is obtained, while the safety is substantially increased.

35 The hollow blades 4 of the radiating network are braced by longitudinal tubes of square cross section; said bracing tubes (Figs. 5 and 6) have a projecting end 22¹ which engages in the opening of the corresponding tube 22² of the adjacent radiator element. This arrangement holds the blades 4 of the various elements 1¹, 1², 1³ in mutual alignment.

40 The locking of the radiator elements thus assembled with each other is effected by rods or stays 14, arranged in the axis of the tubes 8¹, 8², 8³, clamping nuts 15 effecting the locking and clamping the sealing joints 12 interposed between the connections 10, 11.

45 A second emptying header 19 is arranged in the lower part of the radiator. The header 19 is composed of the tubes 19¹, 19², 19³ corresponding to the individual radiator elements 1¹, 1², 1³ and communicates by means of the ascending 50

headers 3 with all the hollow blades 4 of the respective radiator element. The ascending headers 3 open at their upper ends into the headers 8 one of which is provided with the outlet nipple 18 for cooled water.

Finally, the locking of the radiator elements can be completed by outer clamping rods 21 arranged at the lower angles of the radiator elements 1¹, 1², 1³ (Fig. 1).

10 The radiator is advantageously completed by filters 23 lodged in and projecting throughout the length of the individual tubes 8. Consequently the filters 23 have a great surface and can be easily dismounted for cleaning, or repairing by 15 simply disconnecting the elements 1¹, 1², 1³, whereby the interior of the headers 8 becomes accessible and the filters can be easily withdrawn.

To sum up, a radiator of great depth is provided which is easy to keep up and to clean as the 20 mounting of the elements 1¹, 1², 1³ of the radiator can be effected by simply unscrewing the clamping nuts from the stays 14, 21.

The repairing of any of the shallow radiator elements 1¹, 1², 1³ is very simple since all the soldered points are easily accessible and the individual elements are of small weight and bulk. Furthermore, if one of the radiator elements is deteriorated, the interchangeability of the elements permits a speedy replacement of the 30 deteriorated element.

This arrangement renders it also possible to add or to eliminate one or a plurality of elements for tuning up tests of the aeroplane or with respect to considerable variations of temperature, 35 such as occur between winter and summer.

Numerous modifications can be made to the radiator described above by way of example. As shown for instance in Fig. 8, the radiating network can consist of tubes 35 (radiators known as 40 "honeycomb"). In this figure, the headers 6 and 7 serve respectively for the inlet and outlet of the liquid to be cooled.

As in the previous example, the various radiator elements are assembled to each other by stays 45 14 having clamping nuts 15.

To sum up, a cooling radiator is provided for aeroplane engines which has a great depth and a reduced front surface, said radiator being nevertheless easy to mount and to dismount for cleaning and repairs.

Having now particularly described and ascertained the nature of my said invention and in what manner the same is to be performed, I declare that what I claim is:

55 1. In a cooling radiator for aeroplane engines, multiple elements, each comprising a radiating network having hollow blades of small depth, headers for the circulation of the cooling fluid, cross pieces between the headers of the individual 60 elements, bracing tubes having male and female

5 fittings disposed between the blades of the radiating network of each element, said bracing tubes of each element being adapted to be connected with the bracing tubes of the adjacent elements, and removable means mounted on each element for connecting juxtaposed multiple elements to each other.

2. In a cooling radiator for aeroplane engines, 10 multiple elements assembled consecutively to each other in the direction of their own depth, each element comprising a radiating network having hollow blades disposed parallel to the direction of movement, two headers for the inlet of the hot water and the outlet of the cooled water, tubular cylindrical end pieces for said headers disposed 15 parallel to the direction of movement, cross pieces between the headers of the individual elements, nipples arranged in the tubular end pieces of said headers to establish a communication between the headers of one element and those of the adjacent element, and removable connecting means, 20 arranged on each element and fixing the individual assembled elements to each other.

3. In a cooling radiator for aeroplane engines, 25 multiple elements assembled consecutively to each other in the direction of their own depth, each element comprising a radiating network having hollow blades disposed parallel to the direction of movement, two headers for the inlet of the hot water and the outlet of the cooled water, tubular cylindrical end pieces for said headers disposed 30 parallel to the direction of movement, cross pieces between the headers of the individual elements, nipples arranged in the tubular end pieces of said headers to establish a communication between the 35 headers of one element and those of the adjacent element and removable connecting means disposed axially within said headers and fixing the latter and the multiple elements to each other.

4. In a cooling radiator for aeroplane engines, 40 multiple elements assembled consecutively to each other in the direction of their own depth, each element comprising a radiating network having hollow blades disposed parallel to the direction of movement, two headers for the inlet of the hot water and the outlet of the cooled water, tubular end pieces for said headers disposed parallel to the 45 direction of movement, cross pieces between the headers of the individual elements, nipples arranged in the tubular end pieces of said headers to establish a communication between the headers of one element and those of the adjacent element, bracing tubes disposed between the blades of the radiating network of each element and the bracing tubes of the adjacent elements, and removable means mounted on each element for connecting juxtaposed multiple elements to each 50 other.

LOUIS MAURICE LACHASSE. 60
